UNITED STATES PATENT OFFICE.

EZEKIEL J. WILSON, OF EAST GREENBUSH, NEW YORK, ASSIGNOR TO F. C. HUYCK & SONS, OF RENNSSELAER, NEW YORK, A CORPORATION OF NEW YORK.

PAPER-MAKING MACHINE.

Application filed December 2, 1922. Serial No. 604,496.

To all whom it may concern:

Be it known that I, EZEKIEL J. WILSON, a citizen of the United States, residing at East Greenbush, in the county of Rensselaer and State of New York, have invented certain new and useful Improvements in Paper-Making Machines; and I do hereby declare the following to be a full, clear, and exact description of the invention, such as will enable others skilled in the art to which it appertains to make and use the same.

The invention relates to paper making machines.

In these machines the moist web of paper stock formed on the Fourdrinier wire is passed through a series of presses, each one of which is provided with an endless felt and with a pair of pressure rolls between which the felt carries the web of stock.

Each felt is carried on a series of supporting rolls including a felt stretching roll which may be adjusted to regulate the tension on the felt. The proper operation, as well as the life of the felt, is largely dependent upon the maintenance of the proper tension thereon. If the tension is too light the felt will not operate properly upon the web of stock, while too heavy a tension, particularly if continued, will tend

to destroy and shorten the life of the felt. The present invention enables the tension under which the felt is being run to be determined so that proper adjustments may be made to maintain that tension which is best suited to secure the proper operation of the felt on the stock and at the same time prolong the life of the felt. This result is accomplished by the application to each end of one of the rolls over which

the felt runs of means for indicating the pull on the roll due to the tension of the felt passing over it. The tension on each edge of the felt is thus known and proper adjustments of the rolls over which the felt runs

may be made to secure uniform tension throughout the width of the felt. Proper adjustments may also be made to maintain the felt under a tension which will result in its proper operation on the web without danger of applying an unnecessarily heavy tension tending to injure the felt and shorten its life. The indicating devices may be, and preferably are, adapted to record as well as to indicate the tension on the felt during the operation of the ma-

chine. These devices are also preferably so constructed and operated that they may be located at any desired point, however remote from the roll over which the felt is running. The indicating devices may, therefore, be located where they may be most conveniently inspected by the operator or superintendent, and the danger of continued operation of the felts under inefficient conditions, or under excessive tension, thus avoided or reduced to a minimum. The recording of the tension under which the felts are being run also serves as a check on the operator since it will indicate any prolonged inattention to adjustments indicated by variations from the normal tension on any felt.

The invention will be readily understood from the accompanying drawings in which Fig. 1 illustrates diagrammatically the application of the preferred form of the invention to a Fourdrinier paper machine, Fig. 2 is a detailed diagrammatic view showing the mechanism for indicating and recording the pull applied by the felt to the roll over which it runs, and Fig. 3 is a detail plan view illustrating the application of the indicating mechanism to each end of the roll.

In Fig. 1 the Fourdrinier wire on which the paper stock is formed into a web is indicated at 2, the lower couch roll about which the wire passes is indicated at 4, and the upper felt jacketed couch roll which presses the stock into compact web form is indicated at 6. The continuous web of paper stock S formed on the wire passes from the couch rolls through a series of presses, each one of which comprises an endless felt 8 and a pair of press rolls 10 between which the web is carried by the felt. The felt is carried on a series of supporting rolls, including a stretch roll 12 which may be adjusted to regulate the tension under which the felt runs.

In applying the present invention to the machine outlined above one of the felt carrying rolls 14 which lies within a loop of the felt is so mounted that each end may move independently of the other under the pull exerted on the roll by the felt and each end of the roll is connected with a fixed support through a spring link which is distorted by the pull on the roll and by reason of this distortion operates devices which indicate the pull exerted by the felt passing over the

roll. In the construction shown the spring link comprises an elliptical spring 16 one end of which is connected by a hook 18 with the end of the roll, and the other end of which is connected by an adjustable hook 20 with a fixed part 22 of the machine frame. A variation in the pull exerted on the roll 14 by the felt will result in a movement of the sides of the spring 16 toward or away from each other, which movement is proportional to such variation. This movement is utilized to operate an indicating mechanism which may be of any suitable construction, but which is preferably so constructed and operated that its indicating devices may be located at any desired point, however remote from the end of the roll. As shown the indicating means comprises an electric circuit including two synchronized magnetic fields 24 and 26 within which are arranged two similar armatures 28 and 30. The field 28 is mounted on a plate 32 secured to one side of the spring 16 and is connected in series with the field 26 by the wire 34 of an electric circuit so that the field 26 may be located at any desired point, however remote from the field 24. The armature 28 within the field 24 is mounted on the plate 32 so that it may rotate within the field and its position is determined by a rack 36 secured to the other side of the spring 16, and engaging a pinion on the pivot of the armature. The armature 30 is mounted to rotate within the field 26 and is provided at its axis with a pinion engaging a segment 38 which is secured to the pivot 40 of an indicating and recording finger 42. The end of the finger which may carry a recording stylus is arranged to play over a scale which may be graduated to indicate in pounds the pull on the end of the roll 14 or may be graduated to indicate the tension on the felt corresponding to varying positions of the finger. The scale may be formed on a chart arranged to be rotated by clock mechanism and divided into hour periods as is common in recording indicators.

Movement of the sides of the elliptical spring 16 toward or from each other will result in a rotation of the armature 28 within the magnetic field 24 and this will be accompanied by a corresponding movement of the armature 30 within the field 26 and the positions of the armatures within the fields will depend upon the relation of the two sides of the spring to each other and therefore to the pull being exerted upon the roll 14 by the felt passing over it. The finger 42 will, therefore, indicate, or indicate and record, the pull on the corresponding end of the roll 14 or the tension of that edge of the felt passing about this end of the roll. The stretch roll 12 may, therefore, be adjusted to secure the desired tension on the felt and the proper adjustments made to secure an

equal tension at each edge and, therefore, throughout the width of the felt. Whenever there is variation from this normal tension it will be registered by the indicating devices so that it may be immediately observed by the operator and the proper adjustments made to restore the tension to normal. The indicating devices, therefore, enable the operator to make and maintain the adjustments requisite for running the felts under the most desirable and economical conditions and to avoid the application of excessive tension which shortens the life of the felt and destroys its efficiency.

While it is preferred to employ substantially the construction and arrangement of parts shown and described this construction and arrangement is not essential to the broader features of the invention and may be varied or modified as found desirable or best suited to the conditions under which the invention is to be used.

What is claimed is:

1. A paper making machine having, in combination, a felt for supporting the moist web of paper stock and carrying it between press rolls, a roll over which the felt runs, means for indicating the pull exerted on the roll by the felt, and means for regulating the tension of the felt.

2. A paper making machine having, in combination, a felt for supporting the moist web of paper stock and carrying it between press rolls, a roll over which the felt runs, means for indicating the pull exerted on each end of the roll by the felt, and means for regulating the tension of the felt.

3. A paper making machine having, in combination, a felt for supporting the moist web of paper stock and carrying it between press rolls, a roll over which the felt runs, means for recording the pull exerted on the roll by the felt, and means for regulating the tension of the felt.

4. A paper making machine having, in combination, a felt for supporting the moist web of paper stock and carrying it between press rolls, a roll over which the felt runs, a spring link connected to each end of the roll to resist the pull of the felt thereon, and indicating devices operated by the resulting distortion of the link, and means for regulating the tension of the felt.

5. A paper making machine having, in combination, a felt for supporting the moist web of paper stock and carrying it between press rolls, a roll over which the felt runs, means for indicating at a point remote from the roll the pull of the felt thereon, and means for regulating the tension of the felt.

6. A paper making machine having, in combination, a felt for supporting the moist web of paper stock and carrying it between press rolls, means for indicating during the operation of the machine the tension

- under which the felt is running, and means for regulating the tension of the felt.
7. A paper making machine having, in combination, a felt for supporting the moist web of paper stock and carrying it between press rolls, means for recording during the operation of the machine the tension under which the felt is running, and means for regulating the tension of the felt.
8. A paper making machine having, in combination, a felt for supporting the moist web of paper stock and carrying it between press rolls, two synchronized magnetic fields with armatures therein, mechanism connected to relatively move one armature and field in accordance with variations in the tension of the felt, indicating devices actuated by the accompanying relative move-
ment of the other armature and field, and means for regulating the tension of the felt. 20
9. A paper making machine having, in combination, a felt for supporting the moist web of paper stock and carrying it between press rolls, a roll over which the felt runs, a spring link connected to each end of the roll to resist the pull of the felt thereon, two synchronized magnetic fields with armatures therein corresponding to each link, one field and armature being connected to relatively move by distortion of the link, indicating 30 devices connected to be operated by the accompanying movement of the other field and armature, and means for regulating the tension of the felt.

EZEKIEL J. WILSON.
